UNITED STATES PATENT OFFICE.

HENRY L. WALLACE, OF WALLINGFORD, CONNECTICUT, ASSIGNOR TO THE
R. WALLACE & SONS MANUFACTURING COMPANY, OF SAME PLACE.

DESIGN FOR A HANDLE FOR KNIVES, FORKS, &c.

SPECIFICATION forming part of Design No. 26,018, dated September 15, 1896.

Application filed July 2, 1896. Serial No. 597,908. Term of patent 7 years.

To all whom it may concern:

Be it known that I, HENRY L. WALLACE, of Wallingford, in the county of New Haven and State of Connecticut, have invented a new Design for the Handles of Knives, Forks, &c.; and I do hereby declare the following, when taken in connection with the accompanying drawings and the letters of reference marked thereon, to be a full, clear, and exact description of the same, and which said drawings constitute part of this specification, and represent, in—

Figures 1 and 3, side views of handles embodying my design; Fig. 2, a section on line *a b* of Fig. 1.

This invention relates to a design for the handles of knives, forks, and other articles of table-service, and the design consists in the configuration and ornamentation of the handle, as shown in the accompanying illustrations. In general outline the handle is oval in cross-section. Starting from its junction with the body of the knife or fork the handle curves outward, then inward, as at *a*, where it is crossed by a line of beading *b*, then outward, then slightly inward, and gradually outward, as at *b*, forming the body of the handle, then inward and outward, as at *c*, forming the top portion of the handle, which curves inward and is surmounted by a crown *d* of shell-like form. The top portion *c* of the handle is ornamented by a se-

ries of scrolls *A*, inclosing an ornamental panel *B*, as shown in Figs. 1 and 3, but other ornamental panels may be introduced without departing from my design. At the junction of the top portion of the handle with the body thereof is an elaborate foliated and scroll ornamentation *C*, merging into the ornamentation of the body or shank of the handle, which consists of parallel scrolls outlining the handle and inclosing an elongated ornamental panel, as shown in Figs. 1 and 3, but other figures may be introduced into this portion of the handle, as they form no essential part of my design, the salient feature of which is the configuration and scroll and foliated ornamentation. Below these figures is a shell ornament *D*, resting upon the beading *b*, and depending from the beading *b* is a small shell-like ornamentation, in its turn resting upon a transverse raised band *E*, all as shown in the accompanying illustrations.

I claim—

The design for the handles of knives, forks and like articles of table-service, as described and shown in the accompanying illustrations.

In testimony whereof I have signed this specification in the presence of two subscribing witnesses.

HENRY L. WALLACE.
